UNITED STATES PATENT OFFICE.

FRED L. MILLS, OF CHICAGO, ILLINOIS, ASSIGNOR TO MILLS NOVELTY COMPANY, OF CHICAGO, ILLINOIS, A CORPORATION OF ILLINOIS.

TOY RACE COURSE.

Application filed April 12, 1924. Serial No. 706,056.

To all whom it may concern:

Be it known that I, FRED L. MILLS, a citizen of the United States, residing at Oak Park, in the county of Cook and State of Illinois, have invented a new and useful Improvement in Toy Race Courses, of which the following is a specification.

This invention relates particularly to a toy race course and to means for controlling the operation thereof. The control is preferably effected through the medium of a musical instrument, and such musical instrument is preferably of the automatic or semi-automatic type such as a player-piano, an automatic violin machine, a console machine, etc.

Musical machines of the type referred to are on the market, known as the Mills machines. Machines of this character are illustrated in various Letters Patent of the United States, among which may be mentioned Sandell Patent 807,871, granted Dec. 19, 1905, Sandell Patent 855,021, granted May 28, 1907, Sandell Patent 856,604, granted June 11, 1907, Sandell Patent 1,045,444, granted Nov. 26, 1912.

Generally stated, the invention comprises a series of independently movable racing-bodies, dummies, or racers, such as horses, automobiles, bicycles, or the like; and permutation actuating-means for said racers.

The actuating means for the device may be controlled in any suitable manner. Preferably, however, it is controlled by a coin-controlled member of an automatic music machine; and, preferably, the race course is provided with a sequence-changing device which is controlled by note-playing, or note-sounding means of an automatic, or semi-automatic, musical instrument. In the embodiment of the invention illustrated, the racer employed has the form of a horse and rider; the racers are mounted on endless tracks; and the permutably actuating means for the racers comprises a relatively fast-moving permutation-belt equipped with a plurality of longitudinal series of racer-actuating members adapted to permutably engage the racers and vary the sequence in which they move across the area of vision, and a relatively slow-moving endless positioning-belt which carries a member which is adapted to engage all of the racers and

return them to the initial end of the field of vision and place them in position to be 55 permutably engaged by such members of the permutation-belt as may chance to come into position opportunely to engage and advance the racers across the field of vision.

The belts mentioned are of different 60 lengths and so cooperate as to change the combination or sequence in each operation of the device. The permutations thus effected, however, themselves follow a certain sequence, or cycle of sequences. It is preferred, therefore, to provide means for varying the movements of the two belts with 65 relation to each other. Preferably, this is effected by providing means for interrupting the movement of the positioning-belt, and controlling the operation of this sequence-changing through the medium 70 of the note-playing mechanism, or note-controlling mechanism, of a musical instrument. In this manner, the sequence-changing 75 device may be controlled simply and variably by utilizing the playing action which corresponds with the playing of a certain note of a piece of music.

The invention is illustrated in its preferred embodiment in the accompanying drawings, in which—

Figure 1 represents a side elevational view of the improved device, a fragment of the cabinet of a self-playing musical instrument being shown in connection therewith; Fig. 2, a portion of the development of the permutation-belt, this view showing also a portion of the racer-positioning belt and the member actuated thereby; Fig. 3, 85 another portion of the development of said permutation-belt; Fig. 4, an enlarged broken rear elevational view of the left hand portion of the mechanism shown in Fig. 1; Fig. 5, a plan view of the mechanism shown 90 in Fig. 4; Fig. 6, a fragmentary view showing a slightly modified form of a bar constituting a race track; and Fig. 7, a view which is diagrammatic in its nature, and which will facilitate an understanding of 95 the operation of the mechanism and the electric circuits thereof.

In the embodiment illustrated, A represents the frame of the race course; B, the race tracks forming a part of said frame; 100 C, the permutation-belt employed; D, the

racer-positioning belt employed; E, an electric motor whose shaft is geared through a worm and gear connection to a counter-shaft E'; F, a clutch mounted on the 5 countershaft E' and controlling the operation of a pulley or sprocket wheel F', upon which is mounted a belt or sprocket chain F²; G, a drive shaft for the belt D, said shaft being equipped with a pulley or sprocket 10 wheel G' with which the chain F² connects, and equipped with a drum G² upon which one end of the positioning-belt D is mounted; E², a drum secured on the shaft E' and upon which one end of the permutation-belt 15 C is mounted; H, a shaft journaled at the opposite end of the frame and equipped with a drum H' upon which the corresponding end of the belt C is mounted; I, a shaft journaled in the end of the frame beyond 20 the shaft H and equipped with a drum or wheel I' upon which one end of the belt D is mounted; J, a magnet controlling the clutch F; K, a motor-circuit-controlling switch which is controlled by a closing magnet K' and an opening magnet K²; L, a 25 switch controlling the circuit of the clutch-shifting magnet J, and which is operated by a circuit-closing magnet L' and a circuit-opening magnet L²; M, a portion of the 30 note-playing means of a self-playing musical instrument, specifically a tracker-bar of such an instrument; M', a note-sheet controlling the playing of the musical instrument; N, a switch controlling the electric 35 circuits shown; and N', a coin-controlled member which serves as a means for closing the switch N when a coin, or slug, is charged into the machine through a coin chute N².

The improved device preferably is mounted 40 in the cabinet of an automatic or semi-automatic playing musical instrument. For example, the device may be mounted in the cabinet of a self-playing piano, the playing of which is controlled through the medium 45 of a note sheet, a tracker bar, and circuit-controlling contacts co-acting therewith. An illustration of such an arrangement is given in the accompanying drawings. However, the improved device may be mounted 50 in the cabinet of an automatic stringed instrument machine; it may be mounted in the cabinet of a machine provided with stringed instruments of the viol class which are operated or played from a console; or 55 the improved device may be mounted in the cabinet of an ordinary hand-played machine operated through the medium of a key-manual.

The frame A of the device may be of any 60 suitable construction. A' represents the portion of a cabinet of a musical machine which is provided with an elongated view-opening A² which may be covered with a transparency, such as a plate of glass A³. The view-opening A² represents the field

of vision. In Fig. 1, the racers are shown in the position which they occupy at the end of a race. This represents also the position at the beginning of a cycle of operations, it being understood that the motor-circuit was broken when the racers reached the position shown.

The racers are designated by the numerals 1 to 6 inclusive. The corresponding actuating members of these several racers for the 70 race illustrated are designated 1^a to 6^a inclusive in Fig. 2; and the corresponding race tracks, of the series of tracks B are designated in Fig. 5 as 1^b to 6^b inclusive, the front, or near track, 1^b appearing also 80 in Fig. 1.

Each track comprises an endless bar having an upper member 7, a lower member 7^a, a curved initial end 7^b, and a curved final end 7^c, these loops completing the track-circuit. The curves 7^b and 7^c are struck from the centers I and G, respectively, these centers being somewhat below the plane of the centers of the shafts E' and H, which 90 are the centers for the permutation-belt C.

In the illustration given, each racer is shown as representing the figure of a horse and rider. Each racer is movable independently of the other racers. The racer 1, for example, is mounted so as to be capable of moving freely on the track rail 1^b. Thus, the front feet of the horse are shown mounted on a member 8 which is equipped with rollers 8^a which engage the upper and lower edges of the track. The rear feet of the horse are shown mounted on a member 9 equipped with a roller 10 which engages the outer edge of the track. Connected with the lower end of the member 10 is a trigger, or catch-member, 11 which is of an angular 100 form and which has its elbow portion equipped with a roller 11^a which engages the inner edge of the track. The depending arm 11^b of the member 11 is adapted to be engaged by an actuating member of the permutation-belt C. It may also be engaged by a member 13 carried by the positioning-belt D. A spring 12 serves to hold the roller 11^a 110 in engagement with the inner edge of the track. The construction is of a design 115 adapted to permit the racers to move about the curved ends of the track without binding or becoming jammed thereon.

The racer actuating member 1^a which has 120 been designated by reference characters in Figs. 1 and 2, is one of a longitudinal series of such members with which the permutation-belt C is equipped. Any one of these members 1^a may serve to actuate the racer 1, depending upon the combination which 125 chances to be in effect during a race. In a similar manner, the permutation-belt is provided with a longitudinal series of actuating members 2^a, a longitudinal series of actuating members 3^a, etc. These several lon-

gitudinal series are disposed in parallel relation, but the arrangement across the belt is a staggered one, and may be varied, in any desired manner, in the manufacture of the 5 permutation-belt.

The permutation-belt C may be of any desired material. It may, for example, comprise an endless light metal band.

The belt D may comprise an endless metal 10 tape, if desired. It is equipped at one point with a racer actuating member 13. This member is shown as consisting of a light bar of metal which has one end portion 13^a secured to the belt D, a portion 13^b rising 15 therefrom, a cross-bar portion 13^c which is disposed in a high enough plane to avoid contact with the racer actuators mounted on the permutation-belt C, an offset arm 13^d, and an upturned arm 13^e which is equipped 20 with a roller 13^f which engages the rear track 6^b, and thus supports the free end of the member 13.

It will be noted that the upper portion 7 of the track is close enough to the upper 25 side of the permutation-belt to enable the racer actuators 1^a, 2^a, etc., to engage the triggers, or catches, of the racers. On the other hand, the lower portion 7^a of the track is removed so far from the lower side of the 30 permutation-belt that the racer actuators of the permutation-belt cannot engage the fingers, or catches, of the racers during the return movement of the racers at the under-side of the course. This result is accomplished 35 by setting the centers G and I below the centers E' and H.

The motor E may be of any suitable type.

The clutch F serves normally to clutch the pulley or sprocket wheel F' to the shaft E'. The clutch is engaged by a clutch-shifting 40 lever 14 which is mounted on a pivot 14^a and which has its free end within the range of action of the clutch-shifting magnet J. Whenever a certain note of the musical instrument is struck, as occurs, for example, when contact 18 engages the tracker-bar M to energize the circuit 18^a which causes the 45 striking of the note in a well-known manner, the magnet J (assuming its circuit to be closed) is energized and disconnects the sprocket wheel F' from the shaft E' for an instant of greater or less duration, depending upon the length of the note. When the 50 magnet J is de-energized, the clutch is returned to the clutching position by means of a spring 15 (Fig. 5).

The circuits and the method of operation will best be understood from the diagrammatic view shown in Fig. 7, in which the parts are given reference characters corresponding with those employed in the other figures. The mains of the electric circuit are designated 16 and 17. The main 16 has branches 60 16^a and 16^b which are electrically connected with the metal frame A. The branch 16^a

has a sub-branch 16^c leading to one end of the circuit-closing magnet K' and a branch 16^d leading to the switch K. A branch 16^e of the positive side of the circuit also leads to the metal tracker-bar, or roll M. 70

A negative main 17 has a branch 17^a leading to one side of the motor E, and has a branch 17^b leading to one of the members of the switch N. Note-controlling contacts which cooperate with the tracker-bar M are 75 designated 18. These members have circuits 18^a which control the playing of the notes of the musical instrument. One of these contacts, corresponding with a certain note, has connected therewith a conductor 16^f which leads to one end of the clutch-controlling magnet J. On the other end of the magnet J, a conductor 17^c leads to a contact 19 which cooperates with the switch L. From the switch L a conductor 17^d connects with the branch 17^b. From the conductor 17^d, a branch 17^e leads to one end of the magnet L'. 80

The switch K cooperates with a contact point 20 which is connected by a branch 16^g 85 with one side of the motor E. The switch K is adapted to remain in either position after being actuated by either magnet.

The circuit is provided with a contact point 21 which is adapted to be connected with the positive side of the circuit by means of a switch 22 which has an actuating member 22^a which is adapted to be moved to close the circuit by means of an actuating member 23 secured to the belt D. Fig. 7 100 shows the position after the switch 22 has been closed to energize the magnet K² and to interrupt the motor circuit. After such action, the switch 22 returns to the open position. 105

From the contact 21, a branch 16^h extends to one end of the magnet K² and a branch 16ⁱ extends to one end of the magnet L'. On the other end of the magnet K² a branch 17^f extends to the branch 17^b of the negative main. With the branch 17^f there is connected a branch 17^g which connects with one end of the magnet L². With the other end of the magnet L² there is connected a branch 16^j which leads to a contact point 24 which is adapted to be connected with the positive side of the circuit through the medium of a switch 25 which is equipped with an actuating member 25^a. The switch 25 is adapted to be closed when the member 23 on the belt D engages the member 25^a. When this occurs, the circuit of the magnet L² will be energized. This will move the switch L away from the contact 19, and thus break the circuit of the magnet J which controls the clutch F. The main purpose is to prevent the note-playing device of the musical instrument from disconnecting the clutch during the time that the permutation-belt is advancing the racers from the initial 110 115 120 125 130

end of the course to the end of the race (illustrated in Fig. 1). In the illustration given, the clutch-shifting magnet J can be energized as often as the note which controls the actuation of the magnet J is struck during the playing of the musical instrument, but only during that portion of the cycle while the racers are moving from the position shown in Fig. 1 through one-half of the circuit. It is noted, however, that the racer-positioning member 13 does not come into contact with the racers while they are moving from the position shown in Fig. 1 to the transversely alined position at the final end of the range of action of the permutation-belt C. Without some provision for interrupting the circuit of the magnet J, it might happen that the belt D would not bring the member 23 into position to interrupt the motor circuit and stop the race while the racers are within the range of action of the device C. When the clutch is disconnected, the belt D stops for a moment, while the permutation-belt C continues to move. The result of these stoppages is to change the permutation. That is, the permutation will not follow any regular cycle, such as it might follow if one depended merely upon the normal movements of the two belts C and D to effect the change. Every stoppage of the belt D means a lagging of the racers in their return to the initial end of the track; and, since the permutation-belt C continues to move, there is no way of determining which actuating members on the permutation-belt will engage the racers when the racers are brought into the range of action of the actuating members on the permutation-belt.

40 The switch N' controls the starting of the motor (not shown) of the musical instrument in a well known manner. This switch also controls the circuits of the racing device which have been described. However, 45 it is possible, while the musical instrument continues its playing, for the racing device to be actuated a number of times. This may be accomplished by dropping a coin into the instrument and actuating the switch N' 50 whenever it is desired to see the race.

The operation of the device may be restated briefly. When a coin, or slug, closes the switch N', a circuit is established from the positive main 16 through the magnet K', from thence through a branch 17^h to the switch, and from the switch through the branch 17° to the negative main 17. This causes the magnet K' to close the switch K and permit current to pass through the motor E. The motor operates until the member 23 on the belt D actuates the switch 22 and energizes the magnet K², whereupon the magnet K² throws the switch K to the open position. The racers are within the range of vision when the cycle of operation

begins. They may, for example, be located, as represented in Fig. 1. They are carried by the permutation-belt to the left end of the device, as viewed in Fig. 1. After they pass the range of action of the permutation-belt, they are in transverse alinement and remain idle until they are engaged by the racer actuating member 13 mounted on the belt D. They are then moved about the end of the race track and returned at the underside of the race track, and finally brought again to the initial end of the track within the range of action of the permutation-belt and carried to the end of the race, which corresponds, in a general way, with the position of the racers, shown in Fig. 1.

During a portion of the cycle, the positioning-belt may be stopped momentarily, from time to time. Such stoppages occur when the note controlling the circuit of the magnet J is struck, provided the switch L is in the closed position; and the switch L is in the closed position, in the illustration given, while the racers are moved from the position shown in Fig. 1 through one-half of the circuit.

When the racers are carried to the upper portion of the race course, by the positioning-belt, they are brought, in alined relation, across the initial end of the permutation-belt, and are picked up, one after the other, by the projections on the permutation-belt. The sequence, or order, in which the racers move across the field of vision, is varied, however, and such variation is affected, from time to time, by the operation of the musical instrument.

From the description given, it will be understood that while the improved device is capable of operation independently of a musical instrument, it may be used in connection with a musical instrument very advantageously, and will serve to attract interest to the musical instrument. Very expensive musical instruments of the character referred to are now available upon the market; and the use of the improved device as an adjunct, will, without greatly adding to the expense of the installation, enable the receipts from the musical instrument to be very largely increased. For illustration, the rendition of a piece of music on a high-priced instrument may require several minutes of the time of the instrument, and this may be secured for a nickel or a dime. When the improved device is used in connection with the musical instrument, interest may be kept up by inserting coins to enable the races to be watched, and thus the receipts may be increased. The variation in the sequences in which the racers cross the range of vision adds greatly to the interest, and this interest is enhanced by the fact that the change in sequence is effected by the control of the device through the medium of

the mechanism which controls the note-sounding means of the musical instrument.

While, in the embodiment illustrated, the race course is shown in the form of an elongated endless path, it is to be understood that this is only a preferred form for the device.

Any suitable automatic, or semi-automatic musical instrument may have the improved device employed therewith. Those skilled in the art will readily understand that the race course may be controlled in any suitable manner from any desired part of the musical instrument which takes part in the playing-operation. Moreover, it is a feature of advantage that the coin which controls the starting of the musical instrument may serve also to set in operation the improved racing device.

In Fig. 6, B' designates a track-bar having wavy edges, designed to give to the racer a cantering effect as the racer is advanced along the bar.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. In a device of the character set forth, a series of tracks, racer's mounted thereon, a permutation device adapted to actuate said racers, and separate movable means for positioning said racers within the range of action of said permutation device.

2. In a device of the character set forth, a series of independently movable racers, permutation actuating means therefor operative normally to vary the sequence of the racers during each cycle of operation of the device, and additional means for effecting permutation of the normal variation of sequences.

3. In a device of the character set forth, a series of independently movable racers, permutation actuating means therefor operative normally to vary the sequence of the racers during each cycle of operation of the device, and an electro-magnetically operated device adapted to enable the normal variation of sequences to be altered.

4. In a device of the character set forth, a series of independently movable racers, permutation actuating means therefor, normally operative to vary the sequence of the racers and a sequence-changing device for varying the operation of said permutation actuating means.

5. In a device of the character set forth, a series of independently movable racers, permutation actuating means therefor, a sequence-changing device for varying the operation of said permutation actuating means,

and note-playing means of a musical instrument controlling said sequence-changing device.

6. In a device of the character set forth, a series of independently movable racers, 70 actuating means for said racers, and note-playing means of a musical instrument controlling the action of said actuating means and operative to effect a change in sequence of the racers. 75

7. In a device of the character set forth, a series of racers, and permutation actuating means therefor, in combination with a controlling means comprising a note-sheet and attendant mechanism of a self-playing musical instrument. 80

8. In a device of the character set forth, a series of racers, permutation actuating means therefor operative normally to change the sequence of said racers in each cycle of operations, an electric motor for driving said actuating means, means for controlling the operation of said motor, and means for varying the action of said permutation actuating means during the operation of the 90 motor. 85

9. In a device of the character set forth, a series of racers, permutation actuating means therefor, an electric motor serving to drive said actuating means, coin-controlled means controlling the circuit of said motor, and means for varying the operation of said actuating means while it is being driven by said motor, including a controlling device comprising a member of a musical instrument. 100 95

10. In a device of the character set forth, a series of racers, permutation actuating means therefor, an electric motor serving to drive said actuating means, coin-controlled means controlling the circuit of said motor, and means for varying the operation of said actuating means while it is being driven by said motor, including a controlling device comprising a member of a musical instrument. 105 110

11. In a device of the character set forth, a series of racers, permutation actuating means therefor, a motor adapted to drive said actuating means, a device adapted to influence the operation of said permutation actuating means while it is being driven by said motor, and an electromagnet controlling said last-named device. 115 120

12. In a device of the character set forth, a series of independently movable racers, and a permutation actuating device for moving said racers, comprising a permutation member equipped with a plurality of series of actuating members adapted to permutably engage the racers, and a cooperating racer-positioning device having a period of movement different from that of said permutation member. 125 130

13. In a device of the character set forth, a series of independently movable racers, and permutation actuating means therefor, comprising a permutation-belt equipped 5 with a plurality of series of actuating members for permutably engaging the racers, and a cooperating racer-positioning-belt equipped with means for engaging all of the racers.
- 10 14. In a device of the character set forth, a series of independently movable racers, and permutation actuating means therefor, comprising a permutation-belt equipped 15 with a plurality of series of actuating members for permutably engaging the racers, and a cooperating racer-positioning-belt equipped with means for engaging all of the racers, said last-named means being 20 adapted to bring the racers into transverse alignment and position them within the range of action of said permutation-belt.
15. In a device of the character set forth, a series of independently movable racers, and permutation actuating means therefor, comprising a permutation actuating device 25 equipped with a plurality of series of actuating members for permutably engaging the several racers, and a positioning member equipped with means for positioning the racers in substantially transverse alignment 30 and within the range of action of said permutation member.
16. In a device of the character set forth, a series of independently movable racers, and a permutation member equipped with a plurality of series of catch-members for 35 permutably engaging the racers, each of said series corresponding with one of the racers and said series of catch-members moving in an endless path, and a cooperating racer-positioning device equipped with a member adapted to engage all of the racers, said permutation member being driven at a 40 faster rate of speed than said positioning device.
17. In a device of the character set forth, a series of independently movable racers, and permutation actuating means therefor, comprising a permutation-belt equipped 50 with a plurality of series of catch-members for permutably engaging the racers, and a longer racer-positioning-belt equipped with means for engaging all of the racers.
18. In a device of the character set forth, a series of independently movable racers, and permutation actuating means therefor, comprising a permutation-belt equipped 55 with a plurality of series of catch-members for permutably engaging the racers, a longer racer-positioning-belt equipped with means for engaging all of the racers, and means for driving the permutation-belt at one speed 60 and the positioning-belt at a slower speed.
19. In a device of the character set forth, 65 a series of independently movable racers, and permutation actuating means therefor, comprising a permutation-belt equipped with a plurality of series of catch-members for permutably engaging the racers, a longer racer-positioning-belt equipped with means for engaging all of the racers, and means for driving the permutation-belt at one speed and the positioning-belt at a slower speed.
20. In a device of the character set forth, a series of independently movable racers, and permutation actuating means therefor, comprising a permutation-belt equipped 70 with a plurality of series of catch-members for permutably engaging the racers, a longer racer-positioning-belt equipped with means for engaging all of the racers, and means for driving the said belts, and means for interrupting the movements of the positioning-belt.
21. In a device of the character set forth, a series of independently movable racers, and permutation actuating means therefor, comprising a permutation-belt equipped 75 with a plurality of series of catch-members for permutably engaging the racers, a longer racer-positioning-belt equipped with means for engaging all of the racers, and means for driving the said belts, and means controlling the operation of the positioning-belt, including a member of a musical instrument which participates in the sounding of a note of 80 said instrument.
22. In a device of the character set forth, the combination of a series of elongated endless tracks, a series of racers mounted thereon, a permutation-belt equipped with a plurality of series of catch-members adapted 85 to permutably engage the racers, a positioning-belt equipped with means for engaging all the racers, and means for driving said belts at different speeds.
23. In a device of the character set forth, the combination of a series of elongated endless tracks, a series of racers mounted thereon, a permutation-belt equipped with a plurality of series of catch-members adapted 90 to permutably engage the racers, a positioning-belt equipped with means for engaging all the racers, and means for driving said belts variably and with the permutation-belt operating at a greater speed 95 than the positioning-belt.
24. In a device of the character set forth, a series of racers adapted to be moved in an endless course, permutation actuating means therefor adapted to move the racers 100 in permutable sequences through a portion of the course and then bring the racers into substantially transversely alined relation at the final end of the course, and means for engaging the racers after such transverse 105 alinement and returning them to a position within the range of the action of the initial end of said permutation actuating means.
25. In a device of the character set forth, a series of parallel endless race tracks, a series of racers mounted thereon, a permutation-belt equipped with a plurality of series 110 of catch-members for permutably engaging the racers, and means for automatically stopping the motor when the racers occupy 115 a sequence of relative advancement.
26. In a device of the character set forth, a series of parallel endless race tracks, a series of racers mounted thereon, a permutation-belt equipped with a plurality of series 120 of catch-members for permutably engaging the racers, and means for automatically stopping the motor when the racers occupy 125 a sequence of relative advancement.
27. In a device of the character set forth, a series of parallel endless race tracks, a series of racers mounted thereon, a permutation-belt equipped with a plurality of series 130 of catch-members for permutably engaging the racers, and means for automatically stopping the motor when the racers occupy a sequence of relative advancement.

- of catch-members adapted to actuate said racers, a positioning-belt adapted to return the racers to the initial end of the course, a motor serving to drive said belts, a coin-controlled circuit for said motor, and means for breaking said circuit while the racers occupy a sequence corresponding with a sequence of catch-members on said permutation-belt.
- 10 26. In a device of the character set forth, a cabinet provided with an elongated view-opening, and a toy race course in said cabinet comprising a series of substantially parallel endless tracks, racers mounted on said tracks, said view-opening being disposed so as to display said racers while moving across one side of the course and the cabinet serving to conceal the return of the racers to the initial end of the course, and 15 permutation actuating means for said racers, comprising a permutation-belt equipped with a plurality of longitudinal series of catch-members and a positioning-belt equipped with means for engaging all of 20 the racers, said belts being so arranged that the permutation-belt will carry the racers across the field of vision and the positioning-belt will pick up the racers and return them to the initial end of the course.
- 30 27. In a device of the character set forth, a series of endless race tracks, a series of racers mounted thereon, a permutation-belt supported on centers lying in one plane and equipped with a plurality of series of catch 35 members for permutably engaging the racers, a positioning-belt supported on centers disposed at a lower plane, said positioning-belt being of a greater length than the permutation-belt and equipped with a member 40 adapted to engage all the racers and return them to the initial end of the course while the racers are free from engagement with the catch members of the permutation-belt, and driving means for said belts.
- 45 28. In a device of the character set forth, a series of endless race tracks, a series of racers mounted thereon, a permutation-belt supported on centers lying in one plane and equipped with a plurality of series of catch 50 members for permutably engaging the racers, a positioning-belt supported on centers disposed at a lower plane, said positioning-belt being of a greater length than the permutation-belt and equipped with a member 55 adapted to engage all the racers and return them to the initial end of the course while the racers are free from engagement with the catch members of the permutation-belt, driving means for said belts, and means 60 for varying the relative movements of said belts.
29. A cabinet provided with an elongated view opening, and a device mounted in said cabinet comprising a series of racers adapted 65 to be moved through endless paths, permu- tation means adapted to move said racers in varying sequences across the field of vision represented by said view-opening and to return said racers to the initial end of the course, the return movement being hidden 70 by said cabinet and said permutation actuating means being adapted to return the racers, and position them in substantially transverse alinement at the initial end of the course.
- 75 30. In a device of the character set forth, a series of racers adapted to move through endless courses, permutation actuating means therefor, comprising a permutation member equipped with a plurality of series of catch members adapted to permutably engage the racers, a positioning member equipped with means adapted to engage all the racers and return them to the initial end of the course and position them in substantially 80 transverse alinement within the range of action of said permutation member, an electric motor adapted to drive said permutation member and said positioning member, a clutch controlling the drive of said positioning member, an electromagnet controlling said clutch, note-sounding means in a musical instrument controlling said magnet, a motor-controlling-circuit, a circuit controlling said electromagnet, an electromagnet 85 controlling said last-named circuit, and means actuated by said permutation actuating means and serving to control the circuit of said last-named magnet.
- 90 31. In a device of the character set forth, a series of racers adapted to move through endless courses, permutation actuating means therefor, comprising a permutation member equipped with a plurality of series of catch members adapted to permutably engage the racers, a positioning member equipped with means adapted to engage all the racers and return them to the initial end of the course and to position them in sub- 95 stantially transverse alinement within the range of action of said permutation member, an electric motor adapted to drive said permutation member and said positioning member, a clutch controlling the drive of said positioning member, an electro-magnet controlling said clutch, note-sounding means in a musical instrument controlling said magnet, a motor-controlling-circuit, a circuit controlling said electro-magnet, an electromagnet 100 controlling said last-named circuit, means actuated by said permutation actuating means and serving to control the circuit of said last-named magnet, a switch for the motor-circuit, an electromagnet controlling said switch, and a switch controlling said last-named electromagnet and which is itself controlled by the operation of said permutation actuating means.
- 105 32. In a device of the character set forth, a series of substantially parallel endless race 110

tracks, a series of racers mounted thereon equipped with depending fingers, and permutation actuating means comprising a permutation member equipped with a plurality of series of catch members adapted to permutably engage said fingers, and a positioning member equipped with a member adapted to engage all of said fingers and serving to return the racers to the initial 10 end of the course.

33. In a device of the character set forth, a series of substantially parallel endless race tracks disposed in vertical planes, a series of racers mounted thereon, equipped with yielding depending fingers having bearings engaging said tracks, and permutation actuating means equipped with catch members adapted to permutably engage said fingers.

34. In a device of the character set forth, a race course comprising a plurality of parallel tracks, each having upper and lower ways and curved connecting end ways, a plurality of racers mounted on said tracks, an actuating belt equipped with racer-actuators arranged in different positions longitudinally of the belt and which serve to move the racers along the upper ways, a longer belt equipped with means for engaging the racers and moving them through 25 the remainder of their circuits, and means for changing the relative movements of said belts.

35. In a device of the character set forth, a race course comprising a plurality of parallel tracks, each having upper and lower

ways and curved connecting end ways, a plurality of racers mounted on said tracks, an actuating belt equipped with racer-actuators arranged in different positions longitudinally of the belt and which serve to move the racers along the upper ways, a longer belt equipped with means for engaging the racers and moving them through the remainder of their circuits, and recurrently acting means serving to change the 45 relative movements of said belts.

36. In a device of the character set forth, a series of circuits arranged substantially in parallel vertical planes, a series of racers adapted to be moved about said circuits, permutation actuating means adapted to move said racers in permutable sequences through a portion of the course, and means for bringing the racers within range of the initial end 50 of the permutation actuating means.

37. In a device of the character set forth, a cabinet provided with an elongated view-opening and a toy race-course in said cabinet comprising a series of endless tracks arranged in substantially parallel vertical 55 planes and having their upper reaches disposed back of said view-opening, racers mounted on said tracks, permutation actuating means adapted to carry said racers past said view-opening, and means for returning the racers and positioning them within the range of the initial end of said 60 permutation actuating means.

FRED L. MILLS.
